[57] CLAIM

The ornamental design for an umpire's game status keeper, as shown and described.

DESCRIPTION

FIG. 1 is a perspective view of an Umpire's Game Status Keeper showing my design;

FIG. 2 is an enlarged scale perspective view thereof;
FIG. 3 is a right side elevational view thereof, the opposite side being a mirror image;

FIG. 4 is a front elevational view thereof;

FIG. 5 is a rear elevational view thereof;

FIG. 6 is a top plan view thereof; and,

FIG. 7 is a bottom plan view thereof.

The broken lines showing of human figure in FIG. 1 and the indicia in FIGS. 2 and 4 are for illustrative purpose only and forms no part of the claimed design. Surface ornamentation is not shown in FIG. 1 for ease of illustration.
